UNITED STATES PATENT OFFICE

148,907

DESIGN FOR A RADIO CABINET OR THE LIKE

Frank C. Burton, Grand Rapids, Mich., assignor
to Bendix Aviation Corporation, South Bend,
Ind., a corporation of Delaware

Application April 30, 1946, Serial No. 129,141

Term of patent 3½ years

(Cl. D56—4)

To all whom it may concern:

Be it known that I, Frank C. Burton, a citizen
of the United States, residing in Grand Rapids,
in the county of Kent and State of Michigan,
have invented a new, original, and ornamental
Design for a Radio Cabinet, or the like, of which
the following is a specification, reference being
had to the accompanying drawing, forming a part
thereof.

In the drawings:

The single figure is a perspective view of a
radio cabinet or the like, showing my new design;
What is claimed is:

The ornamental design for a radio cabinet or
the like, as shown.

FRANK C. BURTON.
